United States Patent Office

Des. 193,310

Patented July 31, 1962

193,310

EXTRUDER

Robert J. Jacobs, Plainfield, N.J., assignor to Midland-Ross Corporation, Cleveland, Ohio, a corporation of Ohio

Filed July 7, 1960, Ser. No. 61,270

Term of patent 14 years

(Cl. D55—1)

Fig. 1

FIG. 1 is a perspective view taken from the right side of an extruder showing my new design;

FIG. 2 is a perspective view taken from the left side thereof;

FIG. 3 is a top plan view thereof with the portions shown in broken lines in FIGS. 1 and 2 omitted for purposes of illustration.

The dominant features of my design reside in the portions shown in full line.

I claim:

The ornamental design for an extruder, as shown and described.
